(21) Appl. No.: **29/216,741**

CLAIM

(22) Filed: **Nov. 9, 2004**

(51) LOC (8) Cl. **13-03**

The ornamental design for a latch type high definition multimedia interface connector socket, as shown and described.

(52) U.S. Cl. **D13/147**

DESCRIPTION

(58) Field of Classification Search D13/133,
D13/146, 147, 153–154, 184, 199; 439/353,
439/357–358, 362, 372, 558, 606–610, 731

See application file for complete search history.
